(57) **CLAIM**

The ornamental design for a grip for hand-held saw, as shown.

DESCRIPTION

FIG. 1 is a perspective view of a grip for hand-held saw showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom view thereof.

The mark “TAJIMA” appearing on the device shown in the photographic drawings is applicant’s trademark which is registered for other goods in U.S. Trademark Registration Nos. 1,913,048 and 1,953,069.

The portions of the grip for hand-held saw shown in broken lines in the accompanying drawings form no part of the claimed design.
